To all whom it may concern:

Be it known that I, HENRY HUNT, of Greenville, in the county of Hudson and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The design consists of a system of running flower and leaf groups, as shown, which groups 15 rest upon a broken ground, one portion of
